UNITED STATES PATENT OFFICE.

ALPHONSO COMSTOCK PRATT, OF DEEP RIVER, CONNECTICUT, ASSIGNOR, BY MESNE ASSIGNMENTS, TO WHITING & DAVIS COMPANY, OF PLAINVILLE, MASSACHUSETTS, A CORPORATION OF MASSACHUSETTS.

MACHINE FOR MAKING LINK MESH.

Application filed October 11, 1920. Serial No. 416,199.

To all whom it may concern:

Be it known that I, ALPHONSO COMSTOCK PRATT, a citizen of the United States, residing at Deep River, in the county of Middlesex, State of Connecticut, have invented certain new and useful Improvements in Machines for Making Link Mesh; and I do hereby declare the following to be a full, clear, and exact description of the invention, such as will enable others skilled in the art to which it appertains to make and use the same.

This invention relates to machines for making link mesh and has reference particularly to the tools employed in shaping the rings. The invention is of particular utility in connection with mesh machines of the type illustrated in Letters Patent Nos. 948,615 and 1,317,726 heretofore granted to

me.

In such mesh machines, links are made from pieces of straight wire; the wire is fed from a reel and a cutting tool is operated periodically to cut off pieces of equal length. Each piece is then operated upon by forming tools to bend it into the form of a staple and then this staple is moved forward so as to project the legs of the staple through rings in the mesh already formed. Thereafter the staple is operated upon by dies to complete the formation of the ring.

In order to bend the straight wire to the form of a staple it has been customary to employ what is known as a disappearing anvil construction. This includes a movable anvil mounted in the path of movement of a die and presenting a curved surface to the die. The piece of straight wire is fed between the anvil and the die and this die is moved forward to bend the wire about the anvil to form the staple. Immediately after the formation of the staple has been completed, the anvil is caused to move out of the path of the die so that the latter may continue its straight line movement to carry the staple forward for insertion of its legs through rings of the mesh.

In the operation of such mechanisms as they have been constructed heretofore, faulty operation sometimes occurs as a result of slight movement of the straight piece of wire

along the face of the anvil before it is gripped by the cooperating die or by the ends of spring-prongs which are sometimes associated with the die. Even if this movement of the piece of wire be very slight still it may be enough to carry the legs of the staple out of alignment with the legs of the mesh through which they are intended to be projected. Faulty operation in this respect could be avoided if it were permissible to provide a groove in the face of the anvil of a size corresponding to the wire which is being used for then this groove would hold the piece of wire against unintended movement. But the provision of such a groove is not permissible because of the necessity for moving the anvil in the direction of its length to carry it out of the staple immediately after the formation of the staple has been completed so that the die may move forward in a straight line and preferably with a continuous movement.

In accordance with the present invention, the parts are so constructed as to completely eliminate the possibility of such unintended movement of the piece of wire before it is gripped between the parts which bend it into a staple. For this purpose the anvil is made in two parts which are relatively movable and by reason of the fact that it is so made in two parts it is possible to provide in its operative face a groove of substantially the same size as the wire for holding the wire against slippage. The division line between the two parts of the anvil is in a plane passing through the bottom of the groove formed for the reception of the wire. Thus the two parts form an anvil which may be opened at its center by movement of the two parts away from each other and out of the staple. By reason of this formation of the anvil, it is possible to provide a groove in its operative face into which the wire is fed by the wire-feeding means, and when such a groove is provided, the piece of wire when cut off is held against slippage so reliably as to completely eliminate faulty operation of the character referred to.

The invention may be employed in connection with any one of the forms of link-forming tools which have been devised hereto-

fore. In the accompanying drawings I have illustrated it as embodied in a machine of the type illustrated in Patent No. 948,615.

In these drawings, Fig. 1 is a sectional elevation of the machine; Fig. 2 is an enlarged vertical section through the die-rod showing the anvil in elevation; and Fig. 3 is a horizontal section through the link-forming mechanism.

10 Referring to these drawings, 4 indicates a support on which is mounted a mandrel 5 having a spiral thread upon its surface. This mandrel is surrounded by a sleeve 6 having vertical grooves and ridges on its 15 interior surface. The sleeve is rotated step by step in a bearing 7 by a power actuated pawl coating with ratchet teeth 8 on the sleeve. A piece of mesh in the form of a sleeve is adapted to lie in the space between the mandrel 5 and sleeve 6. As the sleeve is rotated step by step the mesh rotates with it by reason of the vertical ridges on the interior of the sleeve and as the mesh is so rotated it is moved upwardly 20 by the spiral thread on the mandrel.

On opposite sides of the mandrel are two sets of link forming tools. Each set is mounted in a block 9 and this block is provided with an opening in which a plunger 10 is adapted to reciprocate. Within the plunger is an opening for the reception of a reciprocating die-rod 11. The outer end of this die-rod passes through a housing 12 and is secured thereto adjustably by nuts 13. Surrounding the die-rod is a coil spring 14 whose ends bear against the housing 12 and plunger 10.

At its inner end the die-rod 11 is provided with a die of semi-circular form. 40 Also, mounted on this end of the die-rod is a sleeve 15, the end of which is shaped to form a pair of prongs 16 and the ends of these prongs are grooved as shown in Fig. 2 to correspond with the wire which is operated upon. The prongs 16 are resilient and are preferably bent inward toward each other a slight amount. The sleeve 15 is adapted to move through a limited range upon the die-rod 11, its movement being limited by the pin 17 on the sleeve entering a short slot 18 on the die-rod.

The end of the plunger 10 is provided with a cutting blade 19. This blade is adapted to cut the wire which is fed from a reel through a bushing 20 mounted on the block.

60 The anvil about which the piece of wire is bent from a straight length to a staple is normally in the path of movement of the die-rod 11 and is arranged to be withdrawn from that path after the formation of the staple is complete. This anvil is shown at 21 in plan in Fig. 3 and in elevation in Fig. 2. As shown in Fig. 2, it is provided with a semi-circular groove of a

size corresponding to the wire. The anvil is formed in two parts, the division between them being in a horizontal plane through the bottom of this groove. Each of the two parts of the anvil is carried by 70 or formed integral with a lever 22 which is pivotally mounted in an opening provided for it in the block 9. Also, as shown in Fig. 1, the plunger 10 is provided with lateral ears each carrying an adjustable 75 stud 23 adapted to engage the end of one of the levers 22 to turn it about its pivot in a direction to carry the portion of the anvil mounted on it out of the path of movement of the die-rod and plunger. The levers 22 carrying the two parts of the anvil are pressed toward each other by springs 24 operating on plungers 25, the springs and their plungers being mounted in openings formed in the block 9.

80 The die-rods 11 are reciprocated by links 26 pivotally mounted in ears projecting from the support 4 and links 27 connecting these levers 26 to a crosshead 28 which is reciprocated vertically by connecting rod 90 85 from a crank 30 on a power shaft 31. The crosshead 28 also reciprocates a cam rod 32 for moving inner dies 33 outwardly in openings formed in the mandrel 5, these inner dies being retracted by springs 34.

90 The wire feeding mechanism feeds the end of the wire through the bushing 20 and across the space between the end of the die rod 11 and the anvil 21, the parts being then in the positions illustrated in Fig. 3. Immediately thereafter the links 26 are rocked in the direction to move the die-rods forward and as the rods so move the springs 14 carried by them operate to move the plungers 10 with the die-rods. The 105 first effect of this movement is to cut the length of wire by means of the cutting blade 19. It will be noted that the anvil 21 is so positioned that when the wire is fed through the bushing 20 and across the 110 space between the anvil and die-rod, it lies partly within the groove in the anvil. Therefore, when the wire is cut by the blade 19 it is supported by the wall of the groove in the anvil so that there is no danger of 115 the wire, after it has been cut, dropping out of position in the moment before it is engaged by the prongs 16 of the sleeve on the die-rod. Immediately after the piece of wire is cut off by blade 19, it is engaged by the prong 16 on the sleeve 15 whose ends are notched to cooperate with the wire.

120 As the parts move forward these prongs bend the wire around the anvil to form a staple and then the semi-circular die-groove 125 in the end of the rod 11 engages the wire. Immediately upon the completion of the formation of the staple the studs 23 carried by the plunger 10 engage the bell crank levers 22, each of which carries half 130

of the anvil 21 and these levers 22 are rocked on their pivots against the tension of their springs 24 to carry one part of the anvil 1 upwardly and the other downwardly 5 out of the path of movement of the die-rod and plunger 10. Then the forward movement of the plunger 10 is arrested by any suitable means and the die-rod moves forward alone carrying the staple with it 10 and projecting the legs of the staple through rings of the mesh on the mandrel. These ends of the legs are carried into contact with the groove in the corresponding inner die 33, which die is moved outwardly by 15 the cam rod 32 at the appropriate time. The prongs 16 on the sleeve 15 engage the end of the inner die 33 and the sleeve 15 is moved backwardly upon the die-rod 11 and the end of die-rod 11 and the inner 20 die 33 come together so as to complete the formation of the link into a ring. The rod 11 is then retracted carrying sleeve 15 with it, and when the sleeve engages the shoulder on the plunger at the rear of the space 25 provided for the reception of the sleeve the latter is moved to its initial position with its prongs projecting beyond the end of the die-rod. Toward the end of the retractile movement of the rod 11, the plunger 10 30 moves with it and as it does so it allows the two parts of the anvil to be brought together again by the springs 24.

It will thus be seen that the construction herein illustrated and described provides 35 for guarding against any slippage of the piece of wire from which a link is formed during the momentary period following the cutting off of the piece of wire for a link and preceding the gripping of that piece of 40 wire between the anvil and the devices which shape the wire about the anvil to form a staple. This is done by providing a groove on the face of the anvil into which the wire is projected when feeding it in position for cutting and the formation of a 45 link. The provision of this groove for so supporting the piece of wire is made possible by the fact that the anvil is made in two parts divided on a plane passing through 50 the bottom of the groove, the two parts being moved in opposite directions away from each other and out of the staple formed on them in order to permit of continuous straight line movement of the die-rod to 55 project the legs of the staple through rings of the mesh and then form the staple into a ring.

In the foregoing I have described my invention as applied to a machine constructed 60 in accordance with the disclosure of Patent No. 948,615, but it will be understood that the invention may be utilized in any form of mesh machine and in connection with link-forming tools of any construction provided only that they include an anvil about

which a piece of wire is bent to the form of a staple by a device which moves up to the anvil and then on to a further position. In particular, it is not necessary to provide special means for engaging the two parts of 70 the anvil and moving them out of the path of the die, such, for instance, as the extensions on the pivoted levers 22 and the abutments 23 which engage those extensions. Instead, the die-member itself may be the 75 element which moves the two parts of the anvil out of its path of movement, as, for instance, by cam surfaces on the die-member and on the anvil parts or by pressure exerted directly from the die-member 80 through the piece of wire to the anvil parts.

I claim:

1. In a machine for making link mesh, a link-forming mechanism for shaping a piece of wire into a staple and for projecting the 85 legs of the staple through links of a piece of mesh and then forming the staple into a link, including an anvil about which a piece of wire is bent to the form of a staple, the said anvil being formed in two parts which 90 are movable relatively to withdraw them from position after the formation of the staple has been completed.

2. In a machine for making link mesh, a link-forming mechanism for shaping a piece 95 of wire into a staple, and for projecting the legs of the staple through links of a piece of mesh and then forming the staple into a link, including a die, an anvil formed in two parts and having a groove therein at 100 the junction of the two parts, means for feeding wire between the die and anvil, means for moving the die to bend a piece of wire about the anvil and then carry that piece of wire to the mesh, and means for 105 moving the two parts of the anvil relatively and out of the path of movement of the die to permit the passage of the die beyond the anvil.

3. In a machine for making link mesh, a 110 die, an anvil formed in two parts and having a groove formed therein at the junction of the two parts, means for feeding wire between the die and anvil so that the wire extends within the said groove, means for 115 moving the die to bend the wire about the anvil to the form of a staple and then to carry the staple to the mesh being formed, and means for moving the two parts of the anvil in opposite directions out of the path 120 of movement of the die immediately after the formation of the staple so that the die may move past the anvil and carry the staple with it.

4. In a machine for making link mesh, a 125 die, an anvil formed in two parts and having a groove therein at the junction of the two parts, two pivoted spring-operated levers, each carrying one of the parts of the anvil, means for feeding wire between the 130

die and the anvil in such position as to cause the wire to lie within the groove in the anvil, means for moving the die to shape a piece of wire about the anvil to form a staple and then to carry the piece of wire to the mesh being formed, and means moving with the die for engaging said levers to

operate them and move the parts of the anvil in opposite directions out of the path of movement of the die immediately after the formation of the staple is completed.

In testimony whereof I affix my signature.

ALPHONSO COMSTOCK PRATT.
